UNITED STATES PATENT OFFICE.

FREEMAN H. OWENS, OF NEW YORK, N. Y.

SOUND AND MOTION-PICTURE REPRODUCING SYSTEM.

Original application filed June 4, 1923, Serial No. 643,154. Divided and this application filed May 19, 1927, Serial No. 192,725. Renewed June 6, 1929.

My invention relates broadly to combined sound and motion picture systems and more particularly to a method of recording sound upon light sensitive film.

5 This application is a division of my application, Serial Number 643,154, filed June 4, 1923.

The object of my invention is to provide a sound recording camera arranged in a 10 telephone circuit with amplifying means in said circuit for subjecting the sensitized film to variable light rays in accordance with the operation of the telephone circuit for transferring telephonic impressions of 15 sound waves on a sensitized film with a sound translating circuit coacting with the light recording system so that the condition of recording on the film may be observed throughout the period of operation of the 20 telephone circuit.

Another object of my invention is to provide a construction of sound recording apparatus with means for observing the operation of the recording apparatus at all times.

25 My invention has been illustrated in the accompanying drawing which shows diagrammatically the arrangement of the telephone circuit and the light recording apparatus with the observing circuit associated 30 therewith.

In the diagram, reference letter C designates the sound transmitting telephone circuit. D represents the sound receiving circuit and E designates an auxiliary sound 35 receiving circuit. The circuit C includes a microphone F and electron tubes H and I constituting an audio frequency amplifier. A telephone G is arranged in the output circuit of the audio frequency amplifier and 40 is acoustically coupled to a chamber J opening to the mouthpiece K of the microphone L of the first sound receiving circuit D.

The sound receiving circuit D includes a 45 lamp A which constitutes part of a sound camera 15 which is mounted on a horizontal slide 19 at one end of a tube or container 20, the opposite end of the container being associated with a coacting plate 21 in which is located a very narrow lateral slit 22 in 50 relation to the film over which a sensitized film 23 is pressed by a roller 27 arranged to move.

In order that the attendant or operator 55 of the camera may hear the sounds as the same are produced or during the acts of

photographing objects in motion and the recording of such sounds, I provide the circuit E including a light reactive cell N arranged in a housing O supported by the container 20 and communicated therewith through a light opening T by the sound recording lamp A. The cell N is arranged in series with the input circuit of the electron tube S and with battery W. The filament electrode of the electron tube S is 60 heated from battery B and there is arranged in the input circuit the inductance V and in the output circuit the inductance U. The output circuit includes high potential source Q and the telephones P'. By this arrangement the microphone F is positioned within the range of the performer and the sound amplified through audio frequency amplifier constituted by tubes H and I, and delivered 65 by the telephone G to the chamber J from which the sounds pass to the microphone L to the first sound receiving circuit. The intensity of the light at the cell A varies with the telephonic current in the circuit D so that the telephonic current is photographically recorded upon the film 23 as it is pulled over the drum 27 by the sprocket 28. In order to check the process of recording on the film, the circuit E is actuated simultaneously with the recording process and any 70 number of branch telephone circuits may extend from this point of headsets P' enabling the camera operator to keep close check upon the recording process. Without the arrangement of my invention, the sound might never be recorded upon the film, as the recording apparatus might be entirely inactive. Large portions of the film might pass the slot 22 without any action from the recording lamp A but with the checking circuit arranged in accordance with my invention, close observation may be made upon 75 the system at all times.

While I have described my invention in its preferred embodiment, I desire that it be 80 understood that modifications may be made and that no limitations upon the invention are intended other than are imposed by the scope of the appended claims.

What I claim as new and desire to secure 85 by Letters Patent of the United States is as follows:

1. In combination, a light source having 90 connected thereto a source of sound modulated electrical energy, a film strip adjacent 95

to said light source, part of the light rays emitted by said light source being directed to said film strip for recording thereon a sound record, a light sensitive cell positioned 5 adjacent to said light source directly in the unobstructed path of light rays emitted from said light source for intercepting a part of said light rays, and connections from said light sensitive element to a sound reproducing circuit.

2. In a system for recording sound upon film, a housing located adjacent said film, a variable light source and an independent light sensitive element projecting into said 15 housing in the path of said light source for receiving light rays directly from said light source, said light source and said light sensitive element being disposed upon the same side of said film strip, means for varying 20 the intensity of said light source in accordance with sound vibrations and independent means connected with said light sensitive element for observing the character of the 25 light fluctuations simultaneously with the impression thereof upon said film.

3. In a system for recording sound upon film, a housing arranged adjacent a film, a variable light source in said housing for variably affecting the film in accordance 30 with sound vibrations, a light sensitive element within said housing in a position adjacent said film and in a position to receive a portion of the rays from said variable light source, said light sensitive element 35 being disposed on the same side of the film as the said light source, and a telephone reproducing circuit connected with said light sensitive element for continuously observing the condition of operation of said variable 40 light source with respect to said film.

4. In a system for determining the changes in intensity of actinic light, an element arranged to emit light, means for controlling the intensity of the emitted light 45 in accordance with sound vibrations, means for establishing a permanent record of the

fluctuations of said emitted light, a light sensitive element positioned directly in the unobstructed path of the emitted light, an electrical circuit controlled by the light sensitive element, and means connected in said 50 electrical circuit and responsive to the changes in condition of said light sensitive element under the influence of the emitted light modulated in accordance with sound vibrations.

5. In a system for recording sound upon film, a source of sound modulated light, the light from said source being passed to a film, a light sensitive element positioned to be affected by said light during its passage to 60 the film and means connected with said light sensitive element for observing the character of said sound modulated light simultaneously with the recording thereof upon the film.

6. In a system for recording sound upon film, a source of sound modulated light, the light from said source being passed to a film, a light sensitive element positioned to be affected by said light during its passage 70 to the film and for translating said light into electric impulses, and means connected to said light sensitive element for rendering said electric impulses audible whereby the character of the sound being recorded may 75 be observed simultaneously with the recording thereof.

7. In combination, a light source having connected thereto a source of sound modulated light, a film strip adjacent to said 80 light source, part of the light rays emitted by said light source being directed to said film strip for recording thereon a sound record, a light sensitive cell positioned adjacent to said light source in the path of 85 light rays emitted from said light source, for intercepting a part of said light rays, and connections from said light sensitive element to a sound reproducing circuit.

In testimony whereof I affix my signature. 90
FREEMAN H. OWENS.
